UNITED STATES PATENT OFFICE.

JOHN C. KAUTZ, OF NEBRASKA CITY, NEBRASKA.

PRINT WASHER.

Application filed July 26, 1923. Serial No. 653,959.

To all whom it may concern:

Be it known that I, JOHN C. KAUTZ, a citizen of the United States, residing at Nebraska City, in the county of Otoe and State of Nebraska, have invented a new and useful Print Washer, of which the following is a specification.

This invention aims to provide a simple means whereby photographic prints may be washed, the washing water in the tank being used as a means for rotating a print carrier in the tank. The invention aims, further to provide novel means for rotating the print carrier and for moving the print carrier into an inoperative position.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:

Figure 1 shows in side elevation a device constructed in accordance with the invention; Figure 2 is an end elevation wherein parts are broken away; Figure 3 is a plan view of the spray head and the water supply pipe; Figure 4 is a sectional view showing a portion of the driving mechanism; Figure 5 is a vertical longitudinal section wherein parts remain in elevation; Figure 6 is a sectional view showing a portion of the water wheel; Figure 7 is a transverse section wherein parts are omitted; Figure 8 is a detail showing one of the pipe connections; Figure 9 is a plan showing a connection which may be interposed in the water supply pipe, if desired.

The print washer forming the subject matter of this application embodies a supporting frame 1 of any desired construction, the frame carrying a tank 2 which is open at the top, the bottom of the tank being curved as shown in Figure 7. A bail-shaped lever 3 is provided and includes side arms 4 of angular form, the side arms extending downwardly into the tank. Near the angles 5 of the side arms of the lever, the side arms

are equipped with downwardly and forwardly inclined slots 6. The rear ends of the side arms 4 of the lever 3 are fulcrumed at 7 on the brackets 8 carried by the frame 1, the forward portions of the side arms of the lever resting on the front wall of the tank 2, as shown in Figure 7 and extending outwardly beyond the forward wall of the tank, so that the lever may be manipulated readily.

A print carrier 9 in the form of a drum is located within the tank 2, and comprises a foraminous body 10 provided with bands 11 and 12 which are joined to the end walls 14 of the tank, the bands 11 and 12 being supplied with outstanding flanges 15, and the band 11 being designated by a separate numeral, because in addition to serving as a reinforcement for the drum 9, it constitutes, also, a portion of the mechanism whereby the drum is rotated. The end walls 14 of the drum 9 are supplied with perforations 16. The end walls 14 of the drum 9 carry stub shafts 17 mounted to rotate in the bearing slots 6 of the side arms 4 of the lever 3, and, when the parts are arranged as shown in Figure 7, the shafts 17 of the drum tend to move by gravity toward the lower forward ends of the slots 6, so that the drum 9 is centered properly with respect to the tank 2, the angular arms 4 of the lever 3 permitting the drum 9 to extend well down into the tank 2. Cross strips 18 and 19 extend between the end bands 11 and 12 of the drum and are connected to the foraminous body 10. A foraminous closure 20 is provided and includes transverse parts 21 and 22, the bar 21 of the closure being united by hinges 23 with the strip 18 of the drum, and the bar 22 of the closure being united detachably by latches 24 with the cross strip 19 on the drum. The closure 20, obviously may be opened to permit the introduction of the prints which are to be washed, into the carrier or drum 9, and to permit the washed prints to be removed from the drum. With this observation, the closure 20 will be dismissed from further consideration.

Along one end wall of the tank 2 extends a substantially vertical conduit 25 (Figures 2 and 5), there being an opening 26 (Figure 5) in the adjacent end wall of the tank 2, this opening being located close to the bottom of the tank. The conduit 25 carries

a spout 27, the spout extending outwardly, as in Figure 5 and being inclined downwardly and extended laterally as shown in Figure 2.

5 The spout 27 discharges into the buckets 28 of an overshot water wheel 29 of liberal diameter, the wheel 29 extending downwardly into a receiving pan 30, mounted on one end of the tank 2 and carrying upon its outer wall, a bearing 31. The shaft 32 of the water wheel 29 is journaled in the bearing 31 and in the inner wall of the receiving pan 30. A drain 33 extends laterally from the lower portion of the receiving pan 30, and is supported on the frame 1, as indicated in Figure 5. The drain 33 has an upstanding branch 34, connected to the bottom of the tank 2, as depicted in Figure 8, a stopper 35 being threaded or mounted otherwise in the upper end of the branch 34.

In Figure 2, the numeral 36 designates, generally, a bearing which is secured to one end wall of the tank 2, the bearing embodying an upstanding inner arm 37 and an upstanding outer arm 38, which are shown in Figures 1 and 4. A hollow shaft 39 is mounted for rotation in the arm 38 of the bearing 36 and is permitted to have a slight vertical movement therein, for a purpose which will be set forth hereinafter. A solid shaft 40 is mounted for longitudinal adjustment in the hollow shaft 39, and the parts 39 and 40, taken together may be al- 30 lowed to as a longitudinally extensible shaft. The shaft 40 carries a cross pin 41 received in elongated slots 42 fashioned in the shaft 39, the function of the pin being to connect the shafts 39 and 40 for longitudinal rotation, and, at the same time, permitting a telescoping of the shafts 39 and 40. The shaft 40 is permitted to have some vertical movement in a vertically elongated slot 43 formed in the arm 37 of the bearing 36. A 35 heavy friction wheel 44 is secured to the inner end of the shaft 40 and is provided with a tread 45, made of rubber or other suitable material, and adapted to bear on the band or track 11 of the drum 9, in- 40 side of the flange 15 of the part 11, as shown clearly in Figures 5 and 1. A sprocket wheel 46 is secured at 47 to the shaft 39, inwardly of the arm 38 of the bearing 36. A sprocket wheel 48 is secured 45 at 49 to the shaft 32 of the water wheel 29. About the sprocket wheels 46 and 48 a sprocket chain 50 is trained.

The means for discharging the washing water into the drum 9 and into the tank 2 may be of any desired sort. For instance, recourse may be had to a horizontal pipe 51, carrying a spray head 52 extended longitudinally of the drum 9, the spray head having perforations 53. If desired, a coupling 54 may be interposed in the pipe 51 as shown

in Figure 9, the construction being such that the spray head 52 and the adjacent portion of the pipe 51 may be swung vertically, for a purpose to be explained hereinafter. It may be desirable to support the 70 spray head 52 in a horizontal position, through the instrumentality of a bracket 55, extended beneath the pipe 51, as shown in Figures 7 and 3.

Water is supplied to the tank 2 through 75 the spray head 52, the water being discharged into the foraminous drum 9. The water, rising in the tank 2, passes through the opening 26 and through the conduit 25, the water being discharged by way of the spout 27 80 on the wheel 29, and rotation being imparted to the drum 9 through a train of elements comprising the shaft 32, the sprocket wheel 48, the sprocket chain 50, the sprocket wheel 46, the longitudinally extensible shaft 39— 85 40, the friction wheel 44—45 and the annular track or wheel 11 of the drum 9. When the drum is rotated, as aforesaid, the prints within the drum will be agitated in 90 the water which the tank 2 contains. Because the opening 26 is located closely adjacent to the bottom of the drum 9, as shown in Figure 5, the chemicals washed from the prints and moving to the bottom of the tank 2 will be drawn away and the prints 95 always will move to a clean body of water. The water in the buckets 28 of the overshot wheel 29 is discharged into the receiving pan 30 and flows away through the drain 33. When it is desirable to draw 100 off the contents of the tank 2 completely, the plug 35 (Figure 8) may be removed, and, thereupon, the contents of the tank will pass through the branch 34 into the 105 pipe 33.

When it is desired to take the prints out of the drum 9, the shaft 40—39 is swung upwardly in the members 37 and 38 of the bearing 36 and the shaft 40 is slid to the right, in Figure 4, into the shaft 39, until the friction wheel 44—45 is clear of the part 11 of the drum 9. If the pipe 51 and the spray head 52 happen to be fixed, the machine may be pulled to the left (Figure 2) until it is well clear of the spray 110 head 52. If, however, the pipe 51 is provided with the connection 54, shown in Figure 9, the pipe may be swung vertically off the support or bracket 55 until it is out of the way of the drum 9. Then, the lever 115 3 may be swung upwardly and backwardly to the right (Figure 7), thereby raising the drum 9 out of the tank 2 and permitting the washed prints to be removed from the drum, when the closure 20 of the drum is 120 opened.

What is claimed is:

1. In a device of the class described, a tank, a water wheel whereto the tank discharges, a print carrier supported for 130

rotation in the tank, a shaft supported for rotation, a wheel on the shaft and cooperating with the carrier to impart rotation thereto, and means for connecting the shaft

5 with the water wheel.

2. In a device of the class described, a tank, a print carrier rotatable in the tank, means for mounting the carrier for raising and lowering, a water wheel whereinto

10 the tank discharges and means for driving the carrier from the water wheel, a portion of said means being movable to permit a

raising and lowering of the carrier.

3. In a device of the class described, a tank, a lever mounted for swinging movement with respect to the tank, a print carrier rotatable in the lever and extended into the tank, the lever constituting means for raising and lowering the carrier, a

20 water wheel whereinto the tank discharges, and means for driving the carrier from the water wheel, a portion of said means being movable to permit a raising and lowering of the carrier through the instru-

25 mentality of the lever.

4. In a device of the class described, a tank, a print carrier rotatable in the tank, means for mounting the carrier for raising and lowering, a water wheel whereinto the

30 tank discharges, a shaft supported for rotation, means for connecting the shaft operatively with the water wheel, and a wheel on the shaft and coacting with the carrier to impart rotation to the carrier, the shaft

35 being longitudinally adjustable to permit the wheel to be moved into and out of engagement with the carrier.

5. In a device of the class described, a tank, a lever mounted for swinging move-
40 ment with respect to the tank, a print car-

rier rotatable in the lever and extended into the tank, a lever constituting means for raising and lowering the carrier, a water wheel whereinto the tank discharges, a shaft supported for rotation, means for connecting the shaft operatively with the water wheel, and a wheel on the shaft and coacting with the carrier, the shaft being longitudinally extensible to permit the wheel to be moved into and out of engagement with

45

50

the carrier, thereby permitting the carrier to be raised and lowered through the instrumentality of the lever.

6. In a device of the class described, a tank, a lever mounted for swinging movement with respect to the tank, a print carrier rotatable in the lever and extended into the tank, the lever constituting means for raising and lowering the carrier, a water wheel supported for rotation, a conduit

60

communicating at its lower end with the tank at a point adjacent to the bottom of the tank, and discharging into the water wheel at a point adjacent to the upper end of the tank, a shaft supported for rotation, a wheel on the shaft and cooperating with the carrier, and means for connecting the shaft operatively with the water wheel, the shaft being longitudinally adjustable to permit the wheel to be moved out of engagement with the carrier, thereby permitting the carrier to be raised through the instrumentality of the lever.
